UNITED STATES PATENT OFFICE.

JAMES M. KANE, OF NEW YORK, N. Y.

SOFT-FOLD COLLAR AND STIFFENING DEVICE THEREFOR.

Application filed June 12, 1920. Serial No. 388,690.

To all whom it may concern:

Be it known that I, JAMES M. KANE, a citizen of the United States, residing at New York, county and State of New York, have 5 invented certain new and useful Improvements in Soft-Fold Collars and Stiffening Devices Therefor, of which the following is a specification.

The principal objects of the invention are 10 to stiffen the ends of the folded-over portion of the collar and to hold them in proper spaced relation. In my preferred form, the stiffening is accomplished by inserting between the plies of fabric, looped members 15 of wire, a member for each end of the folded-over portion. The shorter legs of the loops are adapted to have a link connection between them. In locking the link in place, the shorter legs of the stiffening members 20 or elements are drawn towards each other, causing a bending spring action in them, which tends to hold taut the ends of the soft fold collar.

A still further object of my invention is 25 to so shape the stiffener elements that they can be inserted between the plies of the collar by merely inserting them through a perforation in the lining instead of as is usual by providing special grooves or 30 pockets in the collar.

I attain these objects by the mechanism illustrated in the accompanying drawing:

Figure 1 is a perspective view of a soft 35 fold collar with my improvement shown in place.

Figure 2 is a plan of the right-hand end of the collar opened out flat, showing a stiffener element with the connecting link attached.

Figure 3 is a plan of the left-hand end of 40 the collar opened out flat, showing the other stiffener element.

Figure 4 is a plan of an end of a collar having a rounded front edge showing how the stiffener element is bent to fit.

45 Referring to the drawings wherein the invention is shown in preferred form, the collar consists of a band 10 with the usual button holes 12, and the folded-over portion 11. A portion of the right-hand stiffener 50 element denoted in its entirety by the numeral 23 is inserted between the plies of the folded-over portion 11, through the holes 21 which may be made by forcing the point of a pencil into the lining and turning it about. In inserting stiffener element 23, the

bent-over end of its longer leg 13, is inserted into hole 21, and the element rotated about to follow its bends while it is being slid in. In a similar manner the left-hand stiffener element denoted in its entirety by numeral 60 24, is inserted through hole 22. Stiffener element 23 is in the form of a loop whose longer leg 13 is bent over into a hook. The shorter leg 16 is formed with an eye 27 adapted to engage with the eye of link 29. 65 Stiffener element 24 is similar to stiffener element 23, except that the eye 28 on its shorter leg 20 is suitably shaped to receive the hook end of link 29. The loops 14-15 and 18-19 are in a horizontal position in 70 the collar while the longer legs 13 and 17 lie substantially parallel to the front edges of the folded-over portion along the seam. The shorter legs 16 and 20 are bent at the proper angle to the loops so that the required tension is developed when link 29 hooks into eye 28. The shorter legs 16 and 20 are 75 shown in solid lines in Figures 2 and 3 before link 29 has been hooked into eye 28. The shadow portions of these figures and of 80 Figure 4 show substantially the positions assumed by the various parts of the stiffeners when said hooking has taken place. The spring tendency of shorter legs 16 and 20 to assume the position shown by the solid 85 lines induces tension in link 29, and constant pressure of the longer legs 13 and 17 against the front seams of the collar. The metal of which the stiffener elements is made has substantially the same characteristics as that 90 used for common pins. This material bends with comparative ease and yet has some resiliency. By bending the shorter legs 16 and 20 at the points 25 and 26, the tension 95 between the stiffener elements can be adjusted as well as changing the distance between eyes 27 and 28 to fit collars with wider or narrower spaces between the front edges of the folded-over portions of the collars. For extreme cases different lengths of link 100 29 can be used. The tension developed by link 29 is transferred by bending spring action through loops 14-15 and 18-19 to longer legs 13 and 17 causing them to press 105 against the front seams. By the use of my stiffener elements and their connection, I am also enabled to hold the front edges of the collar up against the necktie with some pressure. By suitably bending the longer legs 110 13 and 17, I can cause these edges to con-

form substantially to the shape of the knot of the necktie, and produce the appearance sometimes desired.

I claim:-

5. 1. A stiffening device for soft fold collars comprising a metallic elastic stiffener element for each front end of the collar and a connecting link hingedly connected to said elements adapted to span across the space 60
10 between said front ends, said stiffener elements being formed of wire suitably bent to permit of their being readily flexed in the direction across said space.
2. A stiffening device for soft fold collars 65
15 comprising a bent wire stiffener element for each front end of the collar, one leg of each stiffener element being bent to conform substantially to its corresponding front end of the collar and means for connecting 70
20 the other legs of said stiffener elements to each other adapted to be under tension and to induce bending spring action in said stiffener elements when the folded over top is down in wearing position.
3. A stiffening device for soft fold collars 75
25 comprising a stiffener element for each front end of the collar, each element being composed of an elastic filament bent into the form of a loop with one leg shorter than the other and means for connecting the shorter legs to each other when the folded over top is down in wearing position.
4. A stiffening device for soft fold collars 80
30 comprising a stiffener element for each front end of the collar, each element being composed of an elastic filament bent into a loop with prolonged legs, the loop portion being substantially at right angles to said legs, one leg adapted to be inserted into the body of the collar and the other leg being 85
35 free, and means for connecting the free legs of each element together when the folded over top is down in wearing position.
5. A stiffening device for soft fold collars, 90
40 comprising a stiffener element for each front end of the collar, each element being composed of an elastic filament adapted to have one end inserted into the collar and the other end free, and a connecting link for 95
45 said free ends provided with a hinged connection at one end and a hook at the other.
6. The combination with a fold collar 100
50 having a band and soft folded-over top of a stiffener element for each end of the

folded-over top, each stiffener element being composed of bent wire and held to the collar by penetrating the lining and means under tension for connecting said stiffener elements to each other when said folded-over top is in wearing position, said stiffener elements being so formed as to be substantially distorted from their normal shape when so connected.

7. The combination with a fold collar 105
55 having a band and soft folded-over top of a stiffener element for each end of the folded-over top, each element being composed of an elastic filament bent into a loop with prolonged legs, the loop portion being held by the collar substantially parallel to the fold, 70
60 the legs being bent substantially at right angles to the loop portion, and means for connecting a leg of one element to one leg of the other.

8. A stiffening device for soft fold collars, 75
65 comprising a stiffener element for each front end of the collar constructed of a bent elastic filament and means spanning across the space between the front ends of the folded over portion for connecting said 80
70 stiffeners one to the other, said filaments being so bent as to cause said connecting means to press outward against the necktie.

9. A stiffening device for soft fold collars 85
80 comprising a stiffener element for each front end of the collar, each element being composed of a length of wire bent into a loop with prolonged legs, one leg of each stiffener adapted to be fastened to the collar, 90
85 the other leg being free, and a wire connecting link hingedly fastened at one end to one of said free legs and having a hook at its other end for engaging with a corresponding eye formed on the other of said free legs.

10. A stiffening device for soft fold collars 95
90 comprising a stiffener element for each front end of the collar, each element being composed of a length of wire bent so as to have two prolonged legs, one leg of each 100
95 stiffener adapted to be fastened to the collar, the other leg being free and adapted to act as a cantilever, said free leg pointing in a substantially downward direction when the folded over top is down in wearing position, 105
100 and a connecting link hingedly fastened to the ends of both of said free legs.

JAMES M. KANE.
